UNITED STATES PATENT OFFICE.

CARL ANDERSEN, LORIS CHRISTIANSEN, LUDVIG FLODIN, AND ALBERT FLODIN, OF COPENHAGEN, DENMARK.

TRAMWAY RAIL.

Application filed September 16, 1924. Serial No. 738,103.

To all whom it may concern:

Be it known that we, CARL ANDERSEN, of Copenhagen, Kobmagergade 59, Denmark, LORIS CHRISTIANSEN, of Copenhagen, 5 Jagtvej 155, Denmark, LUDVIG FLODIN, Copenhagen, Aalekistevej 246, Denmark, and ALBERT FLODIN, at the same place, have invented certain new and useful Improvements in Tramway Rails, of which the following is a specification.

As well known renewal of the imbedded tramway rails requires extraordinary work, all covering material, as asphaltum, concrete etc. having to be broken up and after 15 the renewal of the rails to be remended, which in connection with rejecting of all the rails does not only occasion great expenses, but also an exceedingly grave inconvenience as well for the passengers and 20 the business people living in these streets, the comprehensive works having necessarily to extend over a comparatively long period.

The present invention tends to remedy 25 all these inconveniences by the arrangement, that each rail is formed in two sections, namely an upper head part and a lower part, which latter forms the rail foot, the web and the lowest part of the rail head. The latter is by a zigzag cross cut divided into the two 30 mentioned parts, engaging each other so that a sideway pushing of the uppermost part of the rail head is impossible. In order to prevent also an eventual longitudinal pushing the upper and the lower rail head 35 parts can besides be connected with each other by small steel blocks, lodged in both parts. Moreover the ends of the upper rail parts can like the ends of the lower parts be connected with each other in a well known 40 manner, by autogenous welding or the like so that a longitudinal shifting or pushing is rendered impossible.

A form of the invention is shown in the drawing in which:

45 Figs. 1 and 2 show cross sections of the rail parts separated from each other.

Fig. 3 a cross section through the jointed rail parts.

As shown the cut through the rail head 50 is made so that the uppermost part A at one side has a downward open groove a and on the opposite side a smaller, also downward open groove b, so that at both sides grasping edges c and d respectively are 55 formed. At the same time the part A has

a downward narrowed, deepgoing wedge e. The lowest part B of the rail head has two slanting up- and out-ward directed branches f, g fitting the grooves a, b, and one for the wedge e corresponding to groove h. When the thus formed part A is placed on the part B as shown in Fig. 3, and the whole rail is sunk in the road bed, both parts will act as an integral piece, and a shifting of the part A in a sideway direction is prevented. As mentioned the ends of the rail parts A as well as the ends of the parts B can be united by autogenous welding or the like, and in order to prevent the shifting in the longitudinal direction of the parts there can for each rail length be inserted one or more blocks i of a suitable length in both rail parts A and B.

The two rail parts can easily be made by 65 rolling.

When a rail renewal has to take place, it is not necessary as hitherto to break up the substratum quite down to the rail foot, but only to remove the edge stones, wooden 70 stubs or the like surrounding the rail heads, and thus much time as well as material will be saved.

The cut through the rail head can of course be executed in other ways than this shown. For instance the borders c and d 75 may grasp deeper than shown, and the adjoining planes can moreover engage in each other in any suitable way whatever, if only their engagement is capable of preventing the shifting of the part A on the underlying 80 part B.

Having now described our invention, what we claim is:

1. In a railway rail, a member having a base, a shank and a head, said head having a longitudinal recess in its upper side, the sides of which recess converge downwardly, and also having oppositely downwardly and outwardly inclined upper side edges, and an upstanding flange between one of said inclined upper side edges and one of said sides of said recess; and a member having a head presenting a downwardly extending portion corresponding in cross section with said recess and entering the same, said last named member also having side portions complementary in cross section to the side portions of the first named member.

2. In a railway rail, a member having a base, a shank and a head, said head having 100

- a longitudinal recess in its upper side, the sides of which recess converge downwardly, and also having oppositely downwardly and outwardly inclined upper side edges, and an
5 upstanding flange between one of said inclined upper side edges and one of said sides of said recess; and a member having a head presenting a downwardly extending portion corresponding in cross section with said recess and entering the same, said last named member also having side portions complementary in cross section to the side portions
10 of the first named member, and a spline member arranged in grooves in the portions of the said members forming the bottom of 15 said recess and the bottom of said second named head.

In witness whereof we affix our signatures.

CARL ANDERSEN.
LORIS CHRISTIANSEN.
LUDVIG FLODIN.
ALBERT FLODIN.
